(57) **CLAIM**

The ornamental design for a tee marker, as shown and described.

DESCRIPTION

FIG. 1 is a perspective view of the tee marker of the present design;

FIG. 2 is a front view of the tee marker of FIG. 1; the back view being a mirror image of the front side;

FIG. 3 is a right side elevation view of the tee marker; the left side elevation view being a mirror image of the right side;

FIG. 4 is a top view of the tee marker; and,

FIG. 5 is a bottom view of the tee marker.

The broken lines showing the anchoring elements of the tee marker are for illustrative purposes only and form no part of the claimed design.
